(57) **CLAIM**

The ornamental design for a candy wristwatch, as shown and described.

DESCRIPTION

FIG. 1 is a top perspective view of a candy wristwatch showing my new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof; and,

FIG. 7 is a rear elevational view thereof.

The broken lines showing the cover over the candy sphere on the face of watch dial throughout the drawing figures are for illustrative purposes only and form no part of the claimed design.
